**SOLID TEXTILE DETERGENT
FORMULATION BASED ON GLYCIN-N,
N-DIACETIC ACID DERIVATIVES WITH A
HIGHLY REDUCED PROPORTION OF
OTHER ANIONIC SURFACTANTS**

5

The present invention relates to a solid textile detergent formulation comprising inorganic builders, glycine-N,N-diacetic acid derivatives, with or without small amounts of other anionic surfactants, nonionic surfactants and, if desired, further customary constituents.

Surfactants are the most important group of detergent ingredients. Their content in conventional reduced-phosphate or phosphate-free powder detergents is usually from 10 to 25% by weight. Surfactants detach liquid (oily) and solid fiber soiling during the washing process. However, the detergency of anionic surfactants, in particular, decreases with increasing water hardness. Builders, such as zeolites, are therefore used, their primary purpose being to increase the washing performance of the anionic surfactants by binding the calcium and magnesium ions that are responsible for water hardness.

Some solid soiling contains alkaline earth metal ions, in particular calcium ions. Removal of the calcium ions leads to a loosening of the soil structure and thus facilitates soil detachment from the fiber. In this connection, surfactants require the assistance of water-soluble complexing agents for calcium.

Glycine-N,N-diacetic acid derivatives are surface-active substances of this type. They reduce the surface tension of the washing water and effect soil detachment. They form complexes with Ca and Mg ions, remove particularly effectively calcium-containing soiling and, additionally, support the inorganic builders in their role of softening the washing water and preventing the build-up of fabric incrustations.

The use of said glycine-N,N-diacetic acid derivatives in solid textile detergent formulations is already known from WO-A-97/19159. This patent describes solid textile detergent formulations which comprise, as organic cobuilders, up to 40% by weight of such glycine-N,N-diacetic acid derivatives; these textile detergent formulations further comprise usual amounts of customary anionic surfactants, ie. about 10% by weight or more.

It is an object of the present invention to provide a solid textile detergent formulation in which the content of traditional anionic surfactants is drastically reduced and which comprises a detergents (surface-active) substance which is able to bind calcium and magnesium ions.

We have found that this object is achieved by a solid textile detergent formulation which comprises
(A) from 1 to 60% by weight of inorganic builders based on crystalline or amorphous aluminosilicates, crystalline or amorphous silicates, carbonates and/or phosphates,
(B) from 1 to 40% by weight of one or more glycine-N,N-diacetic acid derivatives of the formula I

(I)

where

R is C₅- to C₃₀-alkyl or C₅- to C₃₀-alkenyl, each of which is unsubstituted or substituted by up to 5 hydroxyl, sulfate, sulfonate, formyl, C₁- to C₄-alkoxy, phenoxy or

C₁- to C₄-alkoxycarbonyl groups, and may be interrupted by up to 5 nonadjacent oxygen and/or nitrogen atoms, R is furthermore alkoxylate of the formula $-(CH_2)_k-O-(A^1O)_m-(A^2O)_n-Y$, where A¹ and A², independently of one another, are 1,2-alkylene having from 2 to 4 carbon atoms, Y is hydrogen, C₁- to C₁₂-alkyl, phenyl, C₁- to C₄-alkoxycarbonyl or sulfo, k is 1, 2 or 3, and m and n are each from 0 to 50, where the sum m+n must be at least 4, phenylalkyl having from 5 to 20 carbon atoms in the alkyl moiety, where the phenyl rings given in the meanings for R are unsubstituted or substituted by up to three C₁- to C₄-alkyl, hydroxyl, carboxyl, sulfo or C₁- to C₄-alkoxycarbonyl groups, or R is a radical of the formula

where A is a C₅- to C₁₂-alkylene bridge and M is hydrogen, alkali metal, alkaline earth metal, ammonium or substituted ammonium in the corresponding stoichiometric quantities,

- (C) from 0 to 6% by weight of anionic surfactants having one or more sulfate groups, one or more sulfonate groups, one or more phosphate groups or one or two carboxylate groups and
(D) from 0.5 to 50% by weight of nonionic surfactants.

The sum of all the detergent components given above and below is at most 100% by weight, including residual quantities of water.

Suitable inorganic builders (A) are in particular crystalline or amorphous aluminosilicates having ion exchange properties, such as, in particular, zeolites. A variety of zeolite types are suitable, in particular zeolites A, X, B, P, MAP and HS in their Na form or in forms in which Na has partially been replaced by other cations, such as Li, K, Ca, Mg or ammonium. Suitable zeolites are described in EP-A 038 591, EP-A 021 491, EP-A 087 035, U.S. Pat. No. 4,604,224, GB-A 20 13 259, EP-A 522 726, EP-A 384 070 and WO-A 94/24251, for example.

Examples of suitable crystalline silicates (A) are disilicates or sheet silicates, eg. $\delta\text{-Na}_2\text{Si}_2\text{O}_5$ or $\beta\text{-Na}_2\text{Si}_2\text{O}_5$ (SKS 6 and SKS 7, Hoechst). The silicates can be used in the form of their alkali metal, alkaline earth metal or ammonium salts, preferably as Na, Li and Mg silicates. Amorphous silicates, for example sodium metasilicate, which has a polymeric structure, or amorphous disilicate (Britesil® H 20, Akzo) can also be used.

Suitable inorganic carbonate-based builder substances (A) are carbonates and hydrogencarbonates. These can be employed in the form of their alkali metal, alkaline earth metal or ammonium salts. Preference is given to carbonates and hydrogencarbonates of Na, Li and Mg, in particular sodium carbonate and/or sodium hydrogencarbonate.

Phosphates which are customarily used as inorganic builders (A) are polyphosphates, for example pentasodium triphosphate.

Said components (A) can be used individually or in mixtures with one another.

Component (A) is preferably present in the textile detergent formulation according to the invention in an amount of from 5 to 50% by weight, in particular from 10 to 45% by weight.

In a preferred embodiment, component (B) comprises compounds I in which R is a radical having at least 7 carbon atoms.

In a particularly preferred embodiment, component (B) comprises glycine-N,N-diacetic acid derivatives I in which R is a linear or branched unsubstituted C₇- to C₃₀-alkyl or C₇- to C₃₀-alkenyl radical, which may be interrupted by up to 5 nonadjacent oxygen and/or nitrogen atoms; said nitrogen atoms may carry hydrogen or C₁- to C₈-alkyl groups.

Compounds I are used in the form of the free acids or their alkali metal, alkaline earth metal, ammonium and substituted ammonium salts. Salts of this type which are especially suitable are the sodium, potassium and ammonium salts, in particular the trisodium, tripotassium and triammonium salts, and also organic triamine salts having a tertiary nitrogen atom.

Particularly suitable parent bases for the organic amine salts are tertiary amines, such as trialkylamines having from 1 to 6 carbon atoms in the alkyl moiety, eg. trimethyl- and triethylamine, methyldiethylamine or tricyclohexylamine, and trialkanolamines having 2 or 3 carbon atoms in the alkanol radical, preferably triethanolamine, tri-n-propanolamine or triisopropanolamine.

Alkaline earth metal salts which may be used are, in particular, the calcium and magnesium salts.

It is possible to employ the racemates of compounds I or the two enantiomers with respect to the a-carbon atom in the glycine backbone.

Suitable linear or branched alk(en)yl radicals as R are C₅- to C₃₀-alkyl and -alkenyl, particularly linear radicals derived from saturated or unsaturated fatty acids. Examples of individual R radicals are: n-pentyl, isopentyl, tert-pentyl, neopentyl, n-hexyl, n-heptyl, 3-heptyl (derived from 2-ethylhexanoic acid), n-octyl, isoctyl (derived from isonanoic acid), n-nonyl, n-decyl, n-undecyl, n-dodecyl, isododecyl (derived from isotridecanoic acid), n-tridecyl, n-tetradecyl, n-pentadecyl, n-hexadecyl, n-heptadecyl, n-octadecyl, n-nonadecyl, n-eicosyl and n-heptadecenyl (derived from oleic acid). R can also be a mixture, in particular one derived from naturally occurring fatty acids and from technical-grade acids produced synthetically, for example by oxo synthesis.

The C₅- to C₁₂-alkylene bridges A are especially polymethylene groups of the formula —(CH₂)_t—, where t is a number from 5 to 12, in particular from 5 to 8, ie. pentamethylene, hexamethylene, heptamethylene, octamethylene, nonamethylene, decamethylene, undecamethylene and dodecamethylene. Hexamethylene and octamethylene are particularly preferred. However, branched C₅- to C₁₂-alkylene groups can also occur, eg. —CH₂CH(CH₃)CH₂—, —CH₂C(CH₃)₂CH₂—, —CH₂CH(C₂H₅)CH₂— or —CH₂CH₂CH(CH₃)CH₂CH₂—.

The C₅- to C₃₀-alkyl and alkenyl groups can carry up to 5, in particular up to 3, additional substituents of said type and be interrupted by up to 5, in particular up to 3, nonadjacent oxygen atoms and/or nitrogen atoms. Examples of such substituted alk(en)yl groups are —CH₂CH₂—O—CH₂CH₂—O—CH₃, —CH₂—O—(CH₂)₄—OH, —CH₂CH₂—N(CH₃)CH₂CH₂CH₃—, —(CH₂)₅—N(CH₃)₂ or —(CH₂—O—CH₂)₅—COOCH₃. Also of interest are substituted alk(en)yl groups of the formula —CH₂CH₂—O—R', where R' is as defined for R with the proviso that R' has at least 3 carbon atoms.

Particularly suitable alkoxylate groups are those in which m and n are each numbers from 0 to 30, especially from 0 to 15. The sum m+n is preferably at least 6, in particular at least 8. A¹ and A² are groups derived from butylene oxide

and, especially, from propylene oxide and from ethylene oxide. Pure ethoxylates and pure propoxylates are of particular interest, although ethylene oxide-propylene oxide block structures may also occur.

If there is any substitution on the phenyl rings, there are preferably two (identical or different) substituents or, in particular, a single substituent.

Examples of phenylalkyl groups are 5-phenylpentyl, 6-phenylhexyl, 8-phenyloctyl, 10-phenyldecyl or 12-phenyldodecyl.

If there is any substitution on the phenyl rings, the substituents are preferably groups which confer solubility in water, such as hydroxyl groups, carboxyl groups or sulfo groups.

Component (B) is preferably present in the textile detergent formulation according to the invention in an amount of from 2 to 30% by weight, in particular from 3 to 20% by weight.

The anionic surfactants (C) are, in principle, taken to mean any anionic surfactants that are structurally different from Compounds I.

In a preferred embodiment, the weight ratio of (B) glycine-N,N-diacetic acid derivatives I to the anionic surfactants (C) in the solid textile detergent formulation according to the invention is from 50:1 to 1:2, preferably from 20:1 to 1:1. The detergent formulation according to the invention is particularly effective in this ratio range.

Examples of suitable anionic surfactants (C) are fatty alcohol sulfates of fatty alcohols having from 8 to 22, preferably from 10 to 18, carbon atoms, eg. C₉- to C₁₁-alcohol sulfates, C₁₂- to C₁₄-alcohol sulfates, C₁₂- to C₁₈-alcohol sulfates, lauryl sulfate, cetyl sulfate, myristyl sulfate, palmityl sulfate, stearyl sulfate and tallow fatty alcohol sulfate.

Further suitable anionic surfactants are sulfated ethoxylated C₈- to C₂₂-alcohols (alkyl ether sulfates) and their soluble salts. Compounds of this type are prepared, for example, by firstly alkoxylating a C₈- to C₂₂, preferably a C₁₀- to C₁₈, alcohol, eg. a fatty alcohol, and subsequently sulfating the alkoxylated product. For the alkoxylation, it is preferable to use ethylene oxide, 1 to 50 mol, preferably 1 to 20 mol of ethylene oxide being employed per mole of alcohol. It is, however, also possible to alkoxylate the alcohols using propylene oxide alone or, if desired, together with butylene oxide. Also suitable are those alkoxylated C₈- to C₂₂-alcohols which contain ethylene oxide and propylene oxide or ethylene oxide and butylene oxide or ethylene oxide and propylene oxide and butylene oxide. The alkoxylated C₈- to C₂₂-alcohols can contain the ethylene oxide, propylene oxide and butylene oxide units in the form of blocks or in random distribution. Depending on the nature of the alkoxylation catalyst, alkyl ether sulfates of broad or narrow alkylene oxide homolog distribution can be obtained.

Further suitable anionic surfactants are alkanesulfonates, such as C₈- to C₂₄-, preferably C₁₀- to C₁₈-, alkanesulfonates, and also soaps, for example the Na and K salts of C₈- to C₂₄-carboxylic acids.

Further suitable anionic surfactants are linear C₈- to C₂₀-alkylbenzenesulfonates ("LAS"), preferably linear C₉- to C₁₃-alkylbenzenesulfonates and -alkyltoluenesulfonates.

Further suitable anionic surfactants (C) are C₈- to C₂₄-olefinsulfonates and -disulfonates, which may also be mixtures of alkene- and hydroxyalkanesulfonates or -disulfonates, alkyl ester sulfonates, sulfonated polycarboxylic acids, alkylglycerolsulfonates, fatty acid glycerol ester sulfonates, alkylphenol polyglycol ether sulfates, par-

affinsulfonates having from about 20 to about 50 carbon atoms (based on paraffin obtained from natural sources or paraffin mixtures), alkyl phosphates, acyl isethionates, acyl taurates, acyl methyltaurates, alkylsuccinic acids, alkenylsuccinic acids or their monoesters or monoamides, alkylsulfosuccinic acids or their amides, mono- and diesters of sulfosuccinic acids, acyl sarcosinates, sulfated alkyl polyglucosides, alkylpolyglycol carboxylates and hydroxyalkyl sarcosinates.

The anionic surfactants are preferably added to the detergent in the form of salts. Suitable cations in these salts are alkali metal ions, such as sodium, potassium and lithium and ammonium salts, for example hydroxyethylammonium, di(hydroxyethyl)ammonium and tri(hydroxyethyl)ammonium salts.

Component (C) is preferably present in the novel textile detergent formulation in an amount of from 0 to 4% by weight, in particular from 0.1 to 4% by weight. Examples of amounts frequently used are from 0 to 0.3% by weight, 0.5% by weight, 1.5% by weight, 2% by weight, 2.5% by weight and 3.5 to 4.5% by weight.

It is possible to use individual anionic surfactants or a combination of different anionic surfactants. It is possible to use anionic surfactants from only one class, for example only fatty alcohol sulfates or only alkylbenzenesulfonates, or mixtures of surfactants from different classes, e.g. a mixture of fatty alcohol sulfates and alkylbenzenesulfonates.

The use of biodegradable glycine-N,N-diacetic acid derivatives I, which also have an incrustation-inhibiting effect, also makes it possible to reduce the content of inorganic builders (A) (in particular aluminosilicates, silicates) and thus to provide concentrated detergent formulations which contain a higher content of biodegradable components.

Accordingly, in a further preferred embodiment, the solid textile detergent formulation according to the invention contains a greatly reduced content of silicate builders, namely: from 1 to 30% by weight, preferably from 5 to 27% by weight, of carbonate-based inorganic builders, from 0 to 12% by weight, preferably from 1.5 to 8% by weight, in particular from 2 to 6% by weight, or preferably from 0 to 0.5% by weight, of inorganic builders based on crystalline or amorphous aluminosilicates and/or crystalline or amorphous silicates and from 0 to 5% by weight, preferably from 0.05 to 2% by weight, of phosphate-based inorganic builders.

Examples of suitable nonionic surfactants (D) are alkoxylated C₈- to C₂₂-alcohols, such as fatty alcohol alkoxylates or oxo alcohol alkoxylates. The alkoxylation can be carried out using ethylene oxide, propylene oxide and/or butylene oxide. Surfactants which can be used are all the alkoxylated alcohols which contain at least two adducted molecules of one of the aforementioned alkylene oxides. Also suitable are block polymers of ethylene oxide, propylene oxide and/or butylene oxide or addition products which contain said alkylene oxides in random distribution. From 2 to 50, preferably from 3 to 20, mol of at least one alkylene oxide are used per mole of alcohol. The alkylene oxide used is preferably ethylene oxide. The alcohols preferably have 10 to 18 carbon atoms. Depending on the type of alkoxylation catalyst, it is possible to obtain alkoxylates with a broad or narrow alkylene oxide homolog distribution.

A further class of suitable nonionic surfactants comprises alkylphenol alkoxylates, such as alkylphenol ethoxylates having C₆- to C₁₄-alkyl chains and from 5 to 30 mol of alkylene oxide units.

Another class of nonionic surfactants comprises alkyl polyglucosides having from 8 to 22, preferably from 10 to 18 carbon atoms in the alkyl chain. These compounds usually contain from 1 to 20, preferably from 1.1 to 5, glucoside units.

Another class of nonionic surfactants comprises N-alkylglucamides having the structures

15 where B¹ is C₆- to C₂₂-alkyl, B² is hydrogen or C₁- to C₄-alkyl and D is polyhydroxyalkyl having from 5 to 12 carbon atoms and at least 3 hydroxy groups. Preferably, B¹ is C₁₀- to C₁₈-alkyl, B² is CH₃ and D is a C₅- or C₆ radical. Such compounds are obtained, for example, by acylating reductively aminated sugars using acid chlorides of C₁₀- to C₁₈-carboxylic acids.

Further suitable nonionic surfactants are the terminally-capped fatty acid amide alkoxylates, known from WO-A 25 95/11225, of the formula

where

R¹ is C₅- to C₂-alkyl or alkenyl,

R² is C₁- to C₄-alkyl,

A¹ is C₂- to C₄-alkylene,

y is 2 or 3 and

x is from 1 to 6.

Examples of such compounds are the reaction products of 35 n-butyltriglycolamine of the formula H₂N-(CH₂-CH₂-O)₃-C₄H₉ and methyl dodecanoate or the reaction products of ethyltetraglycolamine of the formula H₂N-(CH₂-CH₂-O)₄-C₂H₅ and a commercially available mixture of saturated C₈- to C₁₈-fatty acid methyl esters.

40 Further suitable nonionic surfactants (D) are block copolymers of ethylene oxide, propylene oxide and/or butylene oxide (Pluronic® and Tetronic® grades from BASF), polyhydroxy- or polyalkoxyfatty acid derivatives, such as polyhydroxyfatty acid amides, N-alkoxy- or 45 N-aryloxy polyhydroxyfatty acid amides, fatty acid amide ethoxylates, in particular terminally-capped ones, and also fatty acid alkanolamide alkoxylates.

Component (D) is preferably present in the novel textile detergent formulation in an amount of from 1 to 40% by weight, in particular from 3 to 30% by weight, especially from 5 to 25% by weight.

It is possible to use individual nonionic surfactants or a combination of different nonionic surfactants. It is possible to use nonionic surfactants from only one class, in particular only alkoxylated C₈- to C₂₂-alcohols, or mixtures of surfactants from different classes.

In a preferred embodiment, the novel textile detergent formulation comprises, in addition to the inorganic builders (A), from 0.05 to 20% by weight, in particular from 1 to 10% by weight, of organic cobuilders (E) in the form of low molecular weight, oligomeric or polymeric carboxylic acids, in particular polycarboxylic acids, or phosphonic acids or their salts, in particular Na or K salts.

65 Examples of suitable low molecular weight carboxylic acids or phosphonic acids for (E) are: phosphonic acids, for example 1-hydroxyethane-1,1-diphosphonic acid, aminotris(methylenephosphonic

acid), ethylenediaminetetra(methylenephosphonic acid), hexamethylenediaminetetra(methylenephosphonic acid) and diethylenetriaminepenta(methylenephosphonic acid); C₄- to C₂₀-di-, -tri- and -tetracarboxylic acids, for example succinic acid, propanetricarboxylic acid, butanetetracarboxylic acid, cyclopentanetracarboxylic acid and alkyl- and alkenylsuccinic acids having C₂- to C₁₆-alkyl or -alkenyl radicals; C₄- to C₂₀-hydroxycarboxylic acids, for example malic acid, tartaric acid, gluconic acid, glutaric acid, citric acid, lactobionic acid and sucrosemono-, di- and tricarboxylic acid; aminopolycarboxylic acids, for example nitrilotriacetic acid, β -alaninediacetic acid, ethylenediaminetetraacetic acid, serinediacetic acid, isoserinediacetic acid, alkylethylene-diamine triacetate, N,N-bis(carboxymethyl)glutamic acid, ethylenediaminedisuccinic acid, N-(2-hydroxyethyl) iminodiacetic acid and methyl- and ethylglycinediacetic acid.

Examples of suitable oligomeric or polymeric carboxylic acids for (E) are:

oligomaleic acids, as described for example in EP-A 451508 and EP-A 396303; co- and terpolymers of unsaturated C₄-C₈-dicarboxylic acids, possible copolymerized comonomers being mono-ethylenically unsaturated monomers from group (i) in amounts of up to 95% by weight, from group (ii) in amounts of up to 60% by weight and from group (iii) in amounts of up to 20% by weight.

Examples of suitable unsaturated C₄-C₈-dicarboxylic acids in this context are maleic, fumaric, itaconic and citraconic acid. Preference is given to maleic acid.

Group (i) includes monoethylenically unsaturated C₃-C₈-monocarboxylic acids, for example acrylic, methacrylic, crotonic and vinylacetic acid. From group (i), preference is given to acrylic and methacrylic acid.

Group (ii) includes monoethylenically unsaturated C₂-C₂₂-olefins, vinyl alkyl ethers having C₁-C₈-alkyl groups, styrene, vinyl esters of C₁-C₈-carboxylic acids, (meth)acrylamide and vinylpyrrolidone. From group (ii), preference is given to C₂-C₆-olefins, vinyl alkyl ethers having C₁-C₄-alkyl groups, vinyl acetate and vinyl propionate.

Group (iii) includes (meth)acrylic esters of C₁- to C₈-alcohols, (meth)acrylonitrile, (meth)acrylamides of C₁-C₈-amines, N-vinylimidazole.

If the polymers of group (ii) contain copolymerized vinyl esters, they may also, in whole or in part, have been hydrolyzed to give vinyl alcohol structural units. Suitable co- and terpolymers are known from U.S. Pat. No. 3,887,806 and DE-A 43 13 909, for example.

Suitable copolymers of dicarboxylic acids for component (E) are preferably the following:

copolymers of maleic acid and acrylic acid in a weight ratio of from 10:90 to 95:5, particularly preferably those in the weight ratio of from 30:70 to 90:10 having molar masses of from 1000 to 150,000; terpolymers of maleic acid, acrylic acid and a vinyl ester of a C₁-C₃-carboxylic acid in a weight ratio of from 10 (maleic acid):90 (acrylic acid +vinyl ester) to 95 (maleic acid):10 (acrylic acid+vinyl ester), it being possible for the weight ratio of acrylic acid to the vinyl ester to vary from 30:70 to 70:30;

copolymers of maleic acid with C₂-C₈-olefins in a molar ratio of from 40:60 to 80:20, particular preference being given to copolymers of maleic acid with ethylene, propylene or isobutene in a molar ratio of 50:50.

Graft polymers of unsaturated carboxylic acids on low molecular weight carbohydrates or hydrogenated carbohydrates, cf. U.S. Pat. No. 5,227,446, DE-A 44 15 623 and DE-A 43 13 909, are likewise suitable as component (E).

Examples of suitable unsaturated carboxylic acids in this context are maleic, fumaric, itaconic, citraconic, acrylic, methacrylic, crotonic and vinylacetic acid and also mixtures of acrylic acid and maleic acid, which are grafted on in amounts of from 40 to 95% by weight, based on the component to be grafted.

For modification it is additionally possible for up to 30% by weight, based on the component to be grafted, of further monoethylenically unsaturated monomers to be copolymerized. Suitable modifying monomers are the aforementioned monomers of groups (ii) and (iii).

Suitable graft bases are degraded polysaccharides, for example acidic or enzymatically degraded starches, inulins or cellulose, protein hydrolyzates and reduced (hydrogenated or reductively aminated) degraded polysaccharides, for example mannitol, sorbitol, aminosorbitol and N-alkylglucamine, and also polyalkylene glycols having molar masses of up to M_w=5000, for example polyethylene glycols, ethylene oxide-propylene oxide or ethylene oxide-butylene oxide or ethylene oxide-propylene oxide-butylene oxide block copolymers and alkoxylated mono- or polyhydric C₁-C₂₂-alcohols, cf. U.S. Pat. No. 5,756,456.

Polyglyoxylic acids suitable as component (E) are described, for example, in EP-B 001 004, U.S. Pat. No. 5,399,286, DE-A 41 06 355 and EP-A 656 914. The end groups of the polyglyoxylic acids can have different structures.

Polyamidocarboxylic acids and modified polyamidocarboxylic acids suitable as component (E) are known, for example, from EP-A 454 126, EP-B 511 037, WO-A 94/01486 and EP-A 581 452.

Component (E) can also be, in particular, polyaspartic acids or cocondensates of aspartic acid with other amino acids, C₄-C₂₅-mono- or -dicarboxylic acids and/or C₄-C₂₅-mono- or -diamines. Particular preference is given to polyaspartic acids which have been prepared in phosphorus-containing acids and modified with C₆-C₂₂-mono- or -dicarboxylic acids or with C₆-C₂₂-mono- or -diamines.

Component (E) can also be iminosuccinic acid, oxyd succinic acid, aminopolycarboxylates, alkylpolymiocarboxylates, aminopolylethlenephosphonates, polyglutamates, hydrophobically modified citric acid, for example agaric acid, poly- α -hydroxyacrylic acid, N-acylethlenediaminetriacetates, such as lauroylethlenediaminetriacetate, and alkylamides of ethylenediaminetetraacetic acid, such as EDTA-tallow amide.

Furthermore, it is also possible to use oxidized starches as organic cobuilders.

In a further preferred embodiment, the novel textile detergent formulation additionally comprises from 0.5 to 30% by weight, in particular from 5 to 27% by weight, especially from 10 to 23% by weight, of bleaching agents (F) in the form of percarboxylic acids, for example diper-oxododecanedicarboxylic acid, phthalimidopercaproic acid or monoperoxophthalic acid or -terephthalic acid, adducts of hydrogen peroxide with inorganic salts, for example sodium perborate monohydrate, sodium perborate tetrahydrate, sodium carbonate perhydrate or sodium phosphate perhydrate, adducts of hydrogen peroxide with organic compounds, for example urea perhydrate, or of inorganic peroxy salts, for example alkali metal persulfates, or alkali

metal peroxodisulfates, where appropriate, in combination with from 0 to 15% by weight, preferably from 0.1 to 15% by weight, in particular from 0.5 to 8% by weight, of bleach activators (G). In the case of color detergents, the bleaching agent (F) (if present) is normally employed without bleach activator (C); in other cases, bleach activators (G) are usually also present.

Suitable bleach activators (G) include:

polyacetylated sugars, for example pentaacetylglucose; 10
acycloxybenzenesulfonic acids and their alkali metal and alkaline earth metal salts, for example sodium p-nonanoyloxybenzenesulfonate or sodium p-benzoxyloxybenzenesulfonate; N,N-diacylated and N,N,N',N'-tetraacylated amines, for example N,N,N',N'-tetraacetylmethylenediamine and -ethylenediamine (TAED), N,N-diacytylaniline, N,N-diacyetyl-p-toluidine or 1,3-diacylated hydantoins, such as 15
1,3-diacyetyl-5,5-dimethylhydantoin; N-alkyl-N-sulfonylcarbonamides, for example N-methyl-N-mesylacetamide or N-methyl-N-mesylbenzamide; N-acylated cyclic hydrazides, acylated triazoles or urazoles, for example monoacetylmaleic hydrazide; O,N,N-trisubstituted hydroxylamines, for example O-benzoyl-N,N-succinylhydroxylamine, O-acetyl-N,N-succinylhydroxylamine or O,N,N-triacylhydroxylamine; 20
N,N'-diacylsulfurylamides, for example N,N'-dimethyl-N,N'-diacetylsulfurylamine or N,N'-diethyl-N,N'-dipropionylsulfurylamine; acylated lactams, for example acetylcaprolactam, 30
octanoylcaprolactam, benzoylcaprolactam or carbonyl-biscaprolactam; anthranil derivatives, for example 2-methylanthranil or 2-phenylanthranil; triacyl cyanurates, for example triacetyl cyanurate or tribenzoyl cyanurate; 35
oxime esters and bisoxime esters, for example O-acetylacetone oxime or bis(isopropylimino)carbonate; carboxylic anhydrides, for example acetic anhydride, benzoic anhydride, m-chlorobenzoic anhydride or phthalic anhydride; 40
enol esters, for example isopropenyl acetate; 1,3-diacyl-4,5-diacyloxyimidazolines, for example 1,3-diacyetyl-4,5-diacyloxyimidazoline; tetraacetylglycoluril and tetrapropionylglycoluril; 45
diacylated 2,5-diketopiperazines, for example 1,4-diacyl-2,5-diketopiperazine; ammonium-substituted nitrites, for example N-methylmorpholiniumacetonitrile methylsulfate; acylation products of propylenedurea and 2,2-dimethylpropylenedurea, for example tetraacetylpropylenedurea; 50
α-acyloxypolyacylmalonamides, for example α-acetoxy-N,N'-diacetylmalonamide; diacyldioxohexahydro-1,3,5-triazines, for example 1,5-diacyl-2,4-dioxohexahydro-1,3,5-triazine; benz-(4H)1,3-oxazin-4-ones having alkyl radicals, for example methyl, or aromatic radicals, for example phenyl, in the 2-position.

The described bleaching system comprising bleaching agents and bleach activators may, if desired, also contain bleach catalysts. Examples of suitable bleach catalysts are quaternized imines and sulfoneimines, which are described, for example, in U.S. Pat. No. 5,360,569 and EP-A 453 003. Particularly effective bleach catalysts are manganese complexes, which are described, for example, in WO-A 94/21777. Where used, such compounds are incorporated

into the detergent formulations in amounts of up to 1.5% by weight, in particular of up to 0.5% by weight; in the case of very active manganese complexes, amounts of up to 0.1% by weight are used.

5 In addition to the described bleaching system comprising bleaching agents, bleach activators and, if required, bleach catalysts, it is also possible to use systems having enzymatic peroxide release or photoactivated bleaching systems for the novel textile detergent formulation.

In another preferred embodiment, the novel textile detergent formulation additionally comprises from 0.05 to 4% by weight of enzymes (H). Enzymes which are preferably used in detergents are proteases, amylases, lipases and cellulases. Preferred quantities of the enzymes are from 0.1 to 1.5% by weight, in particular from 0.2 to 1.0% by weight, of the formulated enzyme. Examples of suitable proteases are Savinase and Esperase (manufacturer: Novo Nordisk). An example of a suitable lipase is Lipolase (manufacturer: Novo Nordisk). An example of a suitable lipase is Lipolase (manufacturer: Novo Nordisk). An example of a suitable cellulase is Celluzym (manufacturer: Novo Nordisk). It is also possible to use peroxidases to activate the bleaching system. It is possible to use individual enzymes or a combination of different enzymes. If required, the novel textile detergent formulation can also contain enzyme stabilizers, for example calcium propionate, sodium formate or boric acids or salts thereof, and/or antioxidants.

In addition to said main components (A) to (H), the novel textile detergent formulation may also contain the following further customary additives in the amounts customary for this purpose:

cationic surfactants, usually in an amount up to 25% by weight, preferably 3 to 15% by weight, for example C₈- to C₁₆-dialkyldimethylammonium halides, dialkoxydimethylammonium halides or imidazolinium salts having a long-chain alkyl radical;

amphoteric surfactants, usually in an amount up to 15% by weight, preferably from 2 to 10% by weight, for example derivatives of secondary or tertiary amines, for example C₁₂- to C₁₈-alkylbetaines or C₁₂- to C₁₈-alkylsulfobetaines or amine oxides, such as alkylidimethylamine oxides;

antiredeposition agents and soil release polymers (for example, polyesters of polyethylene oxides with ethylene glycol and/or propylene glycol and aromatic dicarboxylic acids or aromatic and aliphatic dicarboxylic acids, or polyesters of polyethylene oxides, terminally-capped at one end, with di- and/or polyhydric alcohols and dicarboxylic acids. Polyesters of this type are known, for example, from U.S. Pat. No. 3,557,039, GB-A-1 154 730, EP-A-0 185 427, EP-A-0 241 984, EP-A-0 241 985, EP-A-0 272 033 and U.S. Pat. No. 5,142,020. Further suitable soil release polymers are amphiphilic graft polymers or copolymers of vinyl esters and/or acrylic esters on polyalkylene oxides, cf. U.S. Pat. No. 4,746,456, U.S. Pat. No. 4,846,995, DE-A-3 711 299, U.S. Pat. No. 4,904,408, U.S. Pat. No. 4,846,994 and U.S. Pat. No. 4,849,126, or modified celluloses, for example methylcellulose, hydroxypropylcellulose or carboxymethylcellulose. Antiredeposition agents and soil release polymers are present in the detergent formulations in amounts of from 0.1 to 2.5% by weight, preferably from 0.2 to 1.5% by weight, particularly preferably from 0.3 to 1.2% by weight. Preferred soil release polymers are the graft polymers, known from U.S. Pat. No. 4,746,456, of vinyl acetate on polyethylene oxide of molar mass 2500-8000 in the weight ratio of from 1.2:1 to 3.0:1, and also

commercially available polyethylene terephthalate/polyoxyethylene terephthalates of molar mass from 3000 to 25,000 comprising polyethylene oxides of molar mass from 750 to 5000 with terephthalic acid and ethylene oxide and a molar ratio of polyethylene terephthalate to polyoxyethylene terephthalate of from 8:1 to 1:1, and the block polycondensates, known from DE-A-44 03 866, which contain blocks of (a) ester units comprising polyalkylene glycols of molar mass 500 to 7500 and aliphatic dicarboxylic acids and/or monohydroxymonocarboxylic acids and (b) ester units comprising aromatic dicarboxylic acids and polyhydric alcohols. These amphiphilic block copolymers have molar masses of from 1500 to 25,000; color transfer inhibitors, for example homo- and copolymers of N-vinylpyrrolidone, of N-vinylimidazole, of N-vinylazolidone or of 4-vinylpyridine N-oxide with molar masses of from 15,000 to 100,000, and also crosslinked, finely divided polymers based on these monomers and having a particle size of from 0.1 to 500, preferably 0.1 to 250 pm; nonsurfactant foam suppressants or foam inhibitors, for example organopolysiloxanes and mixtures thereof with microfine, possibly silanized silicic acid, and also paraffins, waxes, microcrystalline waxes and mixtures thereof with silanized silicic acid; complexing agents (also in the function of organic cobuilders); optical brighteners; polyethylene glycols; perfumes or fragrances; fillers; inorganic extenders, for example sodium sulfate; formulation auxiliaries; solubility improvers; opacifiers and pearlizing agents; dyes; corrosion inhibitors; peroxide stabilizers; electrolytes.

The novel textile detergent formulation is solid, i.e. is usually in powder or granule form or in the form of 45 extrudates or tablets.

The novel pulverulent or granular detergents may contain up to 60% by weight of inorganic extenders. Sodium sulfate is usually used for this purpose. However, the content of extenders in the novel detergents is preferably low and is only up to 20% by weight, particularly preferably only up to 8% by weight, particularly in the case of compact or ultracompact detergents. The novel solid detergents may have various bulk densities in the range from 300 to 1300 50 g/l, in particular from 550 to 1200 g/l. Modern compact detergents generally have high bulk densities and are granular. To achieve the desired compaction of the detergents, it is possible to use the techniques customary in the art.

The textile detergent formulation of the invention is prepared and, if desired, packaged in accordance with customary methods.

The text below gives typical compositions of compact multi-purpose detergents and color detergents (the percentages are by weight; the data in brackets in the case of 65 compositions (a) and (b) are preferred ranges):

(a) Composition of a compact multi-purpose detergent (pulverulent or granular)			
5	1-40%	(2-30%)	of at least one glycine-N,N-diacetic acid derivative (B)
10	5-50%	(10-45%)	of at least one inorganic builder (A)
15	0-6%	(0.1-4%)	of at least one anionic surfactant (C)
20	0.5-50%	(1-40%)	of at least one nonionic surfactant (D)
25	0-20%	(0.5-10%)	of at least one organic cobuilder (E)
30	5-30%	(10-23%)	of an inorganic bleaching agent (F)
35	0.01-15%	(0.5-8%)	of a bleach activator (G)
40	0-1.5%	(0-0.5%)	of a bleach catalyst
45	0-5%	(0.2-2.5%)	of a color transfer inhibitor
50	0-2.5%	(0.2-1.5%)	of a soil release polymer
55	0.05-4%	(0.1-1.5%)	of enzyme or enzyme mixture (H)

Further customary additives:

sodium sulfate, complexing agents, phosphonates, optical brighteners, perfume oils, foam suppressants, antiredeposition agents, bleach stabilizers.

(b) Composition of color detergents (pulverulent or granular)			
25	1-40%	(2-30%)	of at least one glycine-N,N-diacetic acid derivative (B)
30	5-50%	(10-45%)	of at least one inorganic builder (A)
35	0-6%	(0.1-4%)	of at least one anionic surfactant (C)
40	0.5-50%	(1-40%)	of at least one nonionic surfactant (D)
45	0-20%	(0-10%)	of at least one organic cobuilder (E)
50	0-15%	(0-5%)	of an inorganic bleaching agent (F)
55	0-5%	(0-2.5%)	of a color transfer inhibitor
60	0.1-2%	(0.2-1%)	of enzyme or enzyme mixture (H)
65	0-2.5%	(0-1.5%)	of a soil release polymer

Further customary additives:

sodium sulfate, complexing agents, phosphonates, optical brighteners, perfume oils, foam suppressants, antiredeposition agents, bleach stabilizers

EXAMPLES

Unless stated otherwise, all percentages are by weight.

Determination of the primary detergency

The primary detergency tests were carried out using the detergent formulations (DF 1 to 5) detailed in Table 1. Table 2 gives the washing conditions.

TABLE 1

	DF 1 [%]	DF 2 [%]	DF 3 [%]	DF 4 [%]	DF 5 [%]
Lin. alkylbenzenesulfonate	10.00	5.00			
$C_{12}^{\text{—}} \text{ to } C_{18}^{\text{—}}$ alkyl sulfate		5.00		1.50	
$C_{13}^{\text{—}} \text{ to } C_{15}^{\text{—}}$ oxo alcohol $\times 7$ EO	10.00	10.00	10.00	10.00	6.00
AGDA, Na salt			10.00	6.00	6.00
Soap	0.50	0.50		0.50	0.50
Zeolite A	36.00	36.00	36.00	36.00	36.00
Sodium metasilicate $\times 5$ H ₂ O	3.50	3.50	3.50	3.50	3.50
Sodium carbonate	12.00	12.00	12.00	12.00	12.00
Carboxymethyl cellulose	1.50	1.50	1.50	1.50	1.50
Sodium perborate monohydrate	15.00	15.00	15.00	15.00	15.00
TAED	3.50	3.50	3.50	3.50	3.50
Sodium sulfate	4.00	4.00	4.00	4.00	4.00
Water	to	to	to	to	to
	100	100	100	100	100

The abbreviations in Table 1 have the following meanings:

TAED: tetraacetylethylenediamine

AGDA: alkylglycine-N,N-diacetic acid of the formula I 5
where R=a linear C₇-alkyl to C₁₅-alkyl

TABLE 2

Washing conditions:	primary detergency
Washing machine:	Launder-o-meter from Atlas, Chicago, USA
Liquor volume:	250 ml
Washing duration:	30 min at 60° C.
Detergent concentration:	4.0 g/l
Water hardness:	3 mmol/l Ca:Mg = 4:1
Liquor ratio:	12.5:1
Test fabric:	WKF 10D, WKF 20D (WKF-Testgewebe GmbH, D-41379 Brüggen-Bracht) EMPA 101, EMPA 104 (Eidgenössische Materialprüfanstalt, St. Gallen, Switzerland)

The washed test fabrics were measured using a Datacolor photometer (ElrephoO 2000). The total remission values for all four types of fabric are given in percent in each case. The primary detergency is better the higher the remission value.

Results (primary detergency):

TABLE 3

Example	Detergent	AGDA	Total remission [%]
1	WF 1		178.8
2	WF 2		184.7
3	WF 3	C_7 -AGDA	200.9
4	WF 3	C_8 -AGDA	205.3
5	WF 3	C_{10} -AGDA	194.5
6	WF 3	C_{13} -AGDA	192.2
7	WF 4	C_7 -AGDA	199.1
8	WF 4	C_{11} -AGDA	193.6
9	WF 4	C_{15} -AGDA	189.1
10	WF 5	C_7 -AGDA	200.0
11	WF 5	C_9 -AGDA	194.3
12	WF 5	C_{13} -AGDA	185.1

The results show that detergent formulations DP 3 to 5 according to the invention, which have a greatly reduced content of customary anionic surfactants (C), have a clearly better primary detergency than the traditional standard compact detergent formulations DF 1 and 2 (for comparison purposes). The AGDAs bind Ca and Mg ions and thus have an incrustation-inhibiting effect. In view of this ability, the use of AGDAs also makes it possible to reduce markedly the content of inorganic silicate builders (eg. zeolites, sheet silicates, amorphous disilicates), without any loss in performance.

TABLE 4

Table 4 lists, by way of example, compositions [in %] of modern novel compact detergent formulations A to S

TABLE 4-continued

Table 4 lists, by way of example, compositions [in %] of modern novel compact detergent formulations A to S

Constituents	K	L	M	N	O	P	Q

The abbreviations in Table 4 have the following meanings:

(B) from 1 to 40% by weight of one or more glycine-N, N-diacetic acid derivatives of the formula I

TAED:	Tetraacetyl ethylenediamine	45
AGDA:	Alkylglycinediaceitic acid of the formula I where R = a linear C ₇ -alkyl to C ₁₅ -alkyl	
EO:	Ethylene oxide	
Color transfer inhibitor:	Polyvinylpyrrolidone, poly-4-vinyl-pyridine N-oxide or vinylimidazole-vinylpyrrolidone copolymer	50
Incrustation inhibitor:	Acrylic acid-maleic acid copolymer	
Soil release additive 1:	Polyethylene terephthalate/polyoxyethylene terephthalate in a molar ratio of 3:2; molar mass of the condensed polyethylene glycol is 4000, molar mass of the polyester is 10,000	55
Soil release additive 2:	Graft polymer of vinyl acetate on polyethylene glycol having a molar mass of 8000.	60

We claim:

1. A solid textile detergent formulation, comprising:

(A) from 1 to 60% by weight of inorganic builders based on crystalline or amorphous aluminosilicates, crystalline or amorphous silicates, carbonates, phosphates, or mixtures thereof;

wherein

R is

C₅- to C₃₀-alkyl or Ca- to C₃₀-alkenyl, each of which is unsubstituted or substituted by up to 5 hydroxyl, sulfate, sulfonate, formyl, C₁- to C₄-alkoxy, phenoxy or C₁- to C₄-alkoxycarbonyl groups, and may be interrupted by up to 5 nonadjacent oxygen and/or nitrogen atoms, alkoxylate of the formula $-(\text{CH}_2)_k-\text{O}-(\text{A}^1\text{O})_m-(\text{A}^2\text{O})_n-\text{Y}$, where A¹ and A², independently of one another, are 1,2-alkylene having from 2 to 4 carbon atoms, Y is hydrogen, C₁- to C₁₂-alkyl, phenyl, C₁- to C₄-alkoxycarbonyl or sulfo, k is 1, 2 or 3, and m and n are each from 0 to 50, where the sum m+n must be at least 4,

17

phenylalkyl having from 5 to 20 carbon atoms in the alkyl moiety, where all phenyl rings given in the meanings for R are unsubstituted or substituted by up to three C₁- to C₄-alkyl, hydroxyl, carboxyl, sulfo or C₁- to C₄-alkoxycarbonyl
5 or R is a radical of the formula

wherein A is a C₅- to C₁₂-alkylene bridge and
15 M is hydrogen, alkali metal, alkaline earth metal, ammonium or substituted ammonium in the corresponding stoichiometric quantities,

(C) at least one anionic surfactant present in an amount of 6% by weight or less, having one or more sulfate groups, one or more sulfonate groups, one or more phosphate groups or one or two carboxylate groups, and
20

(D) from 0.5 to 50% by weight of nonionic surfactants, wherein the weight ratio of (B) to (C) is from 50:1 to 1:1,
25 in the textile detergent formulation.

2. A solid textile detergent formulation as claimed in claim 1, further comprising:

(E) from 0.05 to 20% by weight of organic cobuilders in the form of low molecular weight, oligomeric or poly-
30 meric carboxylic acids or phosphoric acids or salts thereof.

3. A solid textile detergent formulation as claimed in claim 1, further comprising

(F) from 0.5 to 30% by weight of bleaching agents in the form of percarboxylic acids, adducts of hydrogen peroxide with inorganic salts or organic compounds or of inorganic peroxy salts, and, optionally,
35

(G) from 0.01 to 15% by weight of bleach activators.

4. A solid textile detergent formulation as claimed in claim 1, further comprising:

(H) from 0.05 to 4% by weight of enzymes.

5. A solid textile detergent formulation as claimed in claim 1, wherein R is a radical having at least 7 carbon atoms.
45

6. A solid textile detergent formulation as claimed in claim 1, wherein R is a linear or branched unsubstituted C₇- to C₃₀-alkyl or C₇- to C₃₀-alkenyl radical, which may be interrupted by up to 5 nonadjacent oxygen and/or nitrogen atoms.
50

7. A solid textile detergent formulation as claimed in claim 1, comprising, as component (A),

from 1 to 30% by weight of carbonate-based inorganic builders,

from 0 to 8% by weight of inorganic builders based on crystalline or amorphous aluminosilicates and/or crystalline or amorphous silicates, and

from 0 to 5% by weight of phosphate-based inorganic builders.
60

8. A solid textile detergent formulation as claimed in claim 1, having a bulk density of from 300 to 1300 g/l.

9. A solid textile detergent formulation, comprising:

(A) from 1 to 60% by weight of inorganic builders based on crystalline or amorphous aluminosilicates, crystalline or amorphous silicates, carbonates, phosphates, or mixtures thereof,
65

5

18

(B) from 1 to 40% by weight of one or more glycine-N, N-diacetic acid derivatives of the formula I

10 wherein

R is

C₅- to C₃₀-alkyl or C₁- to C₃₀-alkenyl, each of which is unsubstituted or substituted by up to 5 hydroxyl, sulfate, sulfonate, formyl, C₁- to C₄-alkoxy, phenoxy or C₁- to C₄-alkoxycarbonyl groups, and may be interrupted by up to 5 nonadjacent oxygen and/or nitrogen atoms,

alkoxylate of the formula —(CH₂)_k—O—(A¹O)_m—(A²O)_n—Y, where A¹ and A², independently of one another, are 1,2-alkylene having from 2 to 4 carbon atoms, Y is hydrogen, C₁- to C₁₂-alkyl, phenyl, C₁- to C₄-alkoxycarbonyl or sulfo, k is 1, 2 or 3, and m and n are each from 0 to 50, where the sum m+n must be at least 4,

phenylalkyl having from 5 to 20 carbon atoms in the alkyl moiety, where all phenyl rings given in the meanings for R are unsubstituted or substituted by up to three C₁- to C₄-alkyl, hydroxyl, carboxyl, sulfo or C₁- to C₄-alkoxycarbonyl groups,
or R is a radical of the formula

wherein A is a C₅- to C₁₂-alkylene bridge and M is hydrogen, alkali metal, alkaline earth metal, ammonium or substituted ammonium in the corresponding stoichiometric quantities.

(C) 0% of anionic surfactants having one or more sulfate groups, one or more sulfonate groups, one or more phosphate groups or one or two carboxylate groups, and
45

(D) from 0.5 to 50% by weight of nonionic surfactants.

10. A solid textile detergent formulation as claimed in claim 9, further comprising:

(E) from 0.05 to 20% by weight of organic cobuilders in the form of low molecular weight, oligomeric or polymeric carboxylic acids or phosphoric acids or salts thereof.

11. A solid textile detergent formulation as claimed in claim 9, further comprising

(F) from 0.5 to 30% by weight of bleaching agents in the form of percarboxylic acids, adducts of hydrogen peroxide with inorganic salts or organic compounds or of inorganic peroxy salts, and, optionally,
50

(G) from 0.01 to 15% by weight of bleach activators.

12. A solid textile detergent formulation as claimed in claim 9, further comprising:

(11) from 0.05 to 4% by weight of enzymes.

13. A solid textile detergent formulation as claimed in claim 9, wherein R is a radical having at least 7 carbon atoms.
65

19

14. A solid textile detergent formulation as claimed in claim **9**, wherein R is a linear or branched unsubstituted C₇- to C₃₀-alkyl or C₇- to C₃₀-alkenyl radical, which may be interrupted by up to 5 nonadjacent oxygen and/or nitrogen atoms.

15. A solid textile detergent formulation as claimed in claim **9**, comprising, as component (A),

from 1 to 30% by weight of carbonate-based inorganic builders,

5

20

from 0 to 8% by weight of inorganic builders based on crystalline or amorphous aluminosilicates and/or crystalline or amorphous silicates, and

from 0 to 5% by weight of phosphate-based inorganic builders.

16. A solid textile detergent formulation as claimed in claim **9**, having a bulk density of from 300 to 1300 g/l.

* * * * *
